UNITED STATES PATENT OFFICE.

EDWARD S. SHAW, OF CAMBRIDGE, MASSACHUSETTS.

ELEVATED-RAILWAY SUPERSTRUCTURE AND CAR-TRUCK.

SPECIFICATION forming part of Letters Patent No. 353,086, dated November 23, 1886.

Application filed January 20, 1886. Serial No. 189,130. (No model.)

To all whom it may concern:

Be it known that I, EDWARD S. SHAW, a citizen of the United States, residing at Cambridge, in the county of Middlesex and State of Massachusetts, have invented a new and useful Improvement in Elevated-Railway Superstructures, and in Car-Trucks to be Used Upon the Same, of which the following is a specification, reference being had to the accompanying drawings.

My invention relates to the class of elevated-railway structures in which the principal bearing or track rails are situated on the outside of and below the top of the longitudinal supporting girder or girders; and it consists, principally, in supporting the said track-rails upon brackets or cantilevers attached to the web or web members of the girders and projecting transversely therefrom, so that the rails may be placed near to, but not directly upon, the outer and upper edges of the girders.

It consists, also, in the combination of a pair of flanged plates or shapes of metal attached to the transverse beams or transoms of car or locomotive trucks used upon the structure with a pair of longitudinal guard-rails attached to the girders between and above the level of the track-rails, in order to prevent derailment or overturning arising from wind-pressure, centrifugal force, collisions, &c., substantially as hereinafter more fully set forth.

It consists, also, in the combination of a pair of guard-rails attached to the outer and upper edges of the girders with a flanged guard attached to the trucks of cars or locomotives moving upon the structure, in order to prevent derailment or overturning arising from wind-pressure, centrifugal force, collisions, &c.

It consists, moreover, in the method of attaching the said truck-guard to the car-trucks, and in the construction and arrangement of the car-trucks to this end, so that in case of accident the truck-guard may confine the trucks to the structure, while in ordinary use of the rolling-stock the truck-guard shall not be brought into contact with the guard-rails of the structure in such a manner as to cause appreciable friction or wear of either.

In the accompanying drawings, Figure 1 is a sectional view of the superstructure and truck embodying the first and second part of my in-

vention, the planes of section of the truck being taken on the lines $x x'$ and $y y'$ in Fig. 2. Fig. 2 is a side elevation and sectional view of the truck. Fig. 3 is a sectional view of the superstructure of a narrow-gage railway for a light traffic, operated by electricity; and Fig. 4 is a side elevation of the same, these figures showing the form and manner of attachment of the electrical conductor. Fig. 5 is a sectional view of a superstructure of wood embodying the principle of my invention, and Fig. 6 is a side elevation of the same. In Figs. 3 and 5 the wheels and truck-guards are shown by dotted lines. Fig. 7 is a plan of the superstructure at a turnout from the main line. Figs. 8 and 9 are sectional views of the same, the sections being taken on the lines $x x'$ and $y y'$, respectively, the three latter figures showing the general arrangement and modifications of the structure to be used at a turnout or crossing. Fig. 10 is a section through the bolster, transoms, &c., of the truck, and a longitudinal elevation of the truck-guard with its attachments. Figs. 11, 12, and 14 are side elevations of portions of the transoms of the truck and end elevations of the truck-guard with alternate attachments. Fig. 13 is a plan of the truck-guard and its attachments; and Fig. 15 shows alternative sections of the electrical conductor, together with a plan and elevation of the insulator.

In these several figures the same letters refer to the same parts.

Referring to the drawings, A A' are the top and bottom flanges or chords of the girders, respectively. W V are the web members of the girders. S B is the bracket or cantilever, and b r its connections with the web of the girders. T is the track-rail, and E is an elastic block or wooden stringer, placed underneath the rail.

The form of the girders, and the manner of supporting the same, is not an essential part of my invention. Therefore I may use any known form of girder or truss applicable to my system, and these girders or trusses may be supported by any available form of pier, post, pivot, or abutment, or may rest upon transverse girders, which are in turn supported upon posts or piers.

For example, in Fig. 1 I have shown a pair of plate-girders, consisting of web-plates W,

angle-iron flanges A A', and flange-plates P P', the top plate, P, extending from one girder to the other, connecting the two and forming an open box-girder.

In Figs. 3 and 4, which represent the structure as adapted to a light-weight railway of the narrow or three-foot gage operated by electricity, I have used open-web girders, connecting the top flanges or chords by a lateral bracing 10 of angle-irons and lattice-bars, instead of by a plate, as in Fig. 1.

In Figs. 5 and 6 I have shown an alternative form of the structure, in which wood enters largely into the construction. Here the chords 15 and web verticals of the trusses, together with the transverse brackets, are of wood. The web ties or diagonals, the track and guard rails, and connecting-bolts are iron or steel.

In Fig. 1 the track-rail T is designed with 20 a deep T-rail or inverted deck-beam section, so that it shall act as a beam or stringer, carrying and supporting the weight of the wheels between the brackets. Between the rail and the bracket is placed the block E, of wood, rubber, or of a combination of elastic and non-resonant materials, the construction and composition of which is not a part of this invention.

In Figs. 3, 4, 5, and 6 a shallow rail is shown supported upon a wooden stringer, which sustains 30 the greater part of the weight of the wheels and supplies an elastic bearing.

As I do not claim the specific form and material of the track rail and stringer as a part of my invention, it is evident that I may use 35 any known available shape or substance applicable to my purpose. For example, the rail may have the shape of a bridge or street rail, or may be compound. It may be identical with the stringer, as in Fig. 1, or consist of a 40 separate member, as in Figs. 3, 4, 5, and 6.

To connect the rails or stringers with the brackets, I use the bolts *m n*. These bolts may have hook-shaped heads above, or may pass through lipped washers. They may clasp the 45 rail at their upper ends, or have heads countersunk in the rail or stringer. I also use a lateral bolt and spacer, *t s*, to connect the rail or stringer with the web of the girder, thus preserving the gage. The form, position, and 50 number of these bolts may be varied according to circumstances, as desired.

The bracket or cantilever which is used to support the track should consist of two parts or members—viz., an upper member or shelf, 55 S, having a horizontal upper surface to receive the rail or stringer, and a lower member, brace, or strut, B, which may have its principal plane vertical or slightly inclined, and at right angles to the plane of the girders. One or both of the 60 members of this bracket should be connected with the web or web member of the girder by bolts or rivets. This bracket or cantilever may be constructed in different ways. In Fig. 65 1 it is formed by bending out the upper portion of one of the web verticals or stiffeners of the plate-girder into a horizontal position to form the shelf, and uniting thereto the vertical

plate B, which may be bent at the top into a horizontal plane, thus forming an extension of the shelf S. The brace-plate B is firmly united 70 to the bent-web stiffener by means of rivets.

In the construction shown by Figs. 3 and 4 the shelf is identical with the upper flange of a transversely-placed channel shape, whose web forms the brace B, and is riveted to the 75 web verticals.

In the structure shown in Figs. 5 and 6 the shelf consists of two horizontal scantlings or joists, the brace being a piece of wood bolted between the joists, and toed into and bolted to 80 the web vertical V.

In order to stiffen the web members, and prevent a transverse bending strain, which might be caused by the action of a load upon the brackets, I connect them by an internal lateral 85 bracing, L, which may be a prolongation or extension of one or both members of the brackets, or a separate piece or combination of parts. While this connection and the other internal connections, L' L'' l, are essential to the unity 90 and stability of the structure, and should never be entirely omitted, their form and number will depend upon circumstances, and may be varied.

It is evident that if Warren or triangular 95 girders are used, having no vertical web members, the brackets and connecting-bracing may be attached to the inclined web-struts. In order to do this effectively, the web members should not depart more than thirty degrees 100 from the vertical.

By reference to Figs. 1 and 3 it will be apparent that the outer edge of the upper flange of the girder is very near to the inner edge or flange of a wheel running upon the rail, and 105 that this proximity would in itself tend to prevent derailment. In order, however, to obtain the greatest possible amount of security in exceptional cases—such as the breakage of a wheel or axle, or the action of a powerful 110 wind at right angles to the structure and train, or a collision of trains—I have devised a special guard for the structure, and for the truck, which, acting in co-operation with one another, will confine the trucks to the structure, 115 and prevent derailment or overturning.

The guard upon the structure G will consist in all cases of a rolled shape of iron or steel having a horizontal outwardly-projecting flange, and attached to the girder so as to be 120 somewhat above the upper surface, and on the inner side of the track-rail. It may consist entirely of the upper flange of the girder itself when the girder has a suitably-shaped upper flange or chord, as in Figs. 3 and 4, or it may 125 consist partially or wholly of a separate shape, either attached directly to the upper chords of the girders, as in Figs. 1, 5, and 6, or raised above them by standards or supports, as in Figs. 7, 8, and 9.

The guard upon the truck *g* consists of a double-flanged shape of rolled or forged iron or steel, the upper flange of which is attached to the principal cross-beams or transoms of 130

the trucks, while the lower flange is gaged as to be below the horizontal flange of the guard-rail G.

Now, in the car-trucks as ordinarily constructed the spring-plank is hung considerably below the level of the transoms, and as this is not a suitable member for the attachment of the guard, I have invented a special construction and arrangement of the bolster, bolster-springs, spring plank or tie, and spring-hanger, with the transoms and side frames of the truck, by which the lower surfaces of the transoms are brought below the level of the other transverse members of the truck, and the springs and spring-hangers are spaced further apart laterally than usual, so as not to interfere with the guard.

I use for the upper member or chord of the side frames an angle shape, 4, having one flange horizontal and above, having the other flange vertical and on the outside, placing the bolsters 3 below the upper flange of the angle and extending laterally beneath it. I use for the bolster 3 a channel shape laid flat, with its web uppermost, and trussed by flat bars riveted to it, and for the spring-bearer or spring-tie 6 a channel shape laid flat, with its web lowermost, placed between the transoms above the level of their lower surfaces. I use channel-shaped transoms 2, placing the spring-hangers between them with their upper eyes hung upon a pin passing through the webs of the transoms.

The guard g may be riveted to the lower surfaces of the transoms, and to braces or knees k, or it may be connected with the transoms or knees, or both, by means of bolts passing through spring-washers v z, which by their elasticity will relieve the shock caused by the truck-guard being brought suddenly and violently into contact with the guard-rail on the structure. I also propose in most cases to rivet to the upper flange of the guard g a bent plate or channel-shaped stop or catch, e, which will transfer a part of the longitudinal strain caused by friction of the truck-guard upon the guard-rail to the transoms, and relieve the shearing strain on the connecting rivets or bolts.

The flanged truck-guard g is designed so as to partially inclose, but not usually to touch, the guard-rail upon the structure, the two guards being brought into actual contact only in cases of incipient derailment or overturning. To this end the guard g is so formed and attached as to leave vertical and horizontal spaces between it and the guard-rail G, greater than the usual lateral or vertical motion or difference in position of the transoms of the trucks, caused by the lateral play of the wheels and axles, or by the vertical play of the springs, or by differences in the diameters of the wheels and height of rails caused by original irregularities, wear, &c. Nevertheless, the truck-guard and guard-rail are in such proximity to one another that no unusual or dangerous amount of vertical or lateral motion can ever

occur without the truck-guard being brought into contact with the guard-rail; and preventing further vertical or lateral motion, as well as acting by friction to brake or check the longitudinal motion of the car and train, and for these purposes it is designed and arranged. Its ordinary function is potential, rather than actual, and it is never, except in accidents, subject to friction or wear.

It is evident that in cars or locomotives not provided with bogie-trucks the guard g may be attached to a cross beam or frame situated near and parallel to the axles, and attached and braced to the bottom of the car, or to the side frames of the locomotive. It is also evident that a truck and truck-guard, as herein described, may be used in combination with angle or special shapes of rolled iron or steel, supported upon standards or braces attached to the cross-ties of an ordinary elevated railway or bridge superstructure or truck, or attached to the top lateral connection of girders placed directly beneath the rails, and supporting the rails upon their upper chords.

While I do not specifically claim such combinations, or the method of effecting them, as a part of the present invention, I consider them as novel, and may wish to make them the subject of a future application for Letters Patent.

It is evident that the superstructure herein described may be used for a track having a greater or less degree of lateral curvature by curving the girders laterally so as to be parallel to the track-rails. In curves of slight curvature, having a middle ordinate of three inches or less in the length of a girder, it may not be necessary to curve the girders, but only the track and guard rails, which latter members should in this case be so attached as to permit a lateral variation of distance from the axis of the girder.

In a turnout from the main track of a railway constructed on my system, or at a crossing or junction of intersecting tracks, it will be necessary to vary the method of construction slightly, in order to allow a part of the rails and wheels to cross the girders and guard-rails. This variation is illustrated by the form of construction used at a simple turnout, as shown in Figs. 7, 8, and 9. In this case the upper chords of the girders are placed below the level of the base of the track-rails as shown in Figs. 8 and 9. One of the girders is curved laterally, parallel to the curved inner rail of the turnout, which rail and one of the main track-rails are carried upon transverse brackets attached to the webs of the girders. The other rails are carried over and supported on the tops of the girders, and on the transverse lateral connections and bracing L L', &c. An intermediate beam or girder, F, may be introduced beneath the frog f, extending a greater or less distance longitudinally on either side of it. The guard-rails G are supported upon standards or braces u, Figs. 8 and 9, so as to raise them above the tops of the track-rails. Some of them are curved laterally, so as to be

parallel with the turnout-rails, and are cut off or discontinued for a short distance, near the frog f and switch-points $p p'$, so as to allow the wheels to pass through. It is evident that 5 the spaces caused by the breaks in the guard-rails may be filled by short rails hinged or pivoted at one end, and moved at the other end laterally, like the switch-points, being operated by mechanism controlled by the same lever that is used to throw the switch.

In order to operate the railway herein described by electro-dynamic motors actuated by a current conveyed along the line, it will be necessary to provide a suitable conductor or conductors for the transmission of the electric current. This might be done by insulating the track-rails and using them as conductors for currents, contact being made with the girders to ground the current. As, however, there are practical difficulties in the way of insulating track-rails, and at the same time connecting them securely with the structure, I consider it better to apply a special conductor of iron or other metal to the top of the girders. As the space between the under side of the transoms of the trucks and top of the girders is quite limited, the conductor must be designed to occupy as little space vertically as possible. It must also be of such shape as to allow of connections at its joints having a sectional area nearly equal to its own, and situated so as not to obstruct the passage over it of a contact-wheel, brush, or spring. A conductor shaped like a laterally elongated bridge or Barlow rail, or of crescent form, with the convex side uppermost, will accomplish these ends. The conductor is attached to the top or top lateral connections of the girder or girders, either in the middle or near to one side, by bolts passing through circular shaped washers of a non-conducting material, having an annular groove to receive the lip or edge of the conductor. The conductors are to be connected at their joints by a metal plate, filling the space beneath them, and attached to them by bolts or rivets countersunk on top. The forms and application of the conductors and insulators are shown by Figs. 15, 3, and 4.

I do not claim, broadly, as my invention the position of the track-rails on the outside of and below the top of a longitudinal girder or girders; neither do I claim, generally, the use of brackets projecting laterally from the girder or girders and supporting the rails; nor, in general, a method of preventing derailment dependent upon the use of the girders as guards, or by means of guards or guides situated inside of and above the level of the rails, or by the use of a hooked guard or flanged attachment to a car or car-truck acting in combination with a guard-rail on or attached to the girders.

What I do claim as my invention, and desire to secure by Letters Patent of the United States, is—

1. A longitudinal superstructure or permanent way for an elevated railway consisting

of a double girder, or of a pair of connected girders or trusses, placed between two track-rails and supporting the track-rails in proximity to the upper and outer corners of the girders by means of cantilevers or brackets attached to and projecting transversely from the web or web members of the girders or trusses, the position and relation of the principal parts of the structure being substantially as herein shown and described. 75

2. In combination with the longitudinal girder or girders of an elevated-railway superstructure, cantilevers or brackets attached to 80 and projecting transversely from the web or web members of the girder or girders, each bracket consisting of an upper horizontal member or shelf, S , receiving a longitudinal track stringer or rail, and a lower vertical or inclined member, strut, or brace, B , re-enforcing the upper member or shelf, S , the position of the brackets with reference to the girders and rails being substantially as herein shown and described. 85

3. In combination with the longitudinal girders A V W A' and transverse brackets S B , of an elevated-railway superstructure, the transverse or lateral connections and internal bracing L L' L'' l uniting the girders and 95 brackets, substantially as and for the purposes set forth.

4. In combination with a pair of flanged plates or guards attached to the transverse beams of a car or locomotive truck, a pair of longitudinal guard-rails, G , situated between and above the inner and upper corners of the track-rails and attached to the longitudinal girders, each guard-rail being provided with a flange projecting outwardly in proximity to 100 and above the inwardly-projecting lower flange of the truck-guard g , substantially as shown and described.

5. In an elevated-railway superstructure, the combination of longitudinal girders A V W A' , transverse cantilevers or brackets S B , track-rails T , elastic blocks or stringers E , lateral bracing L L' L'' l , guard-rails G , and connections m n s t b r , &c., substantially as and for the purposes set forth. 110

6. In a truck for an elevated-railway superstructure as herein described, the combination of the wheels 1 , principal transverse beams or transoms 2 , bolster 3 , side frames, 4 , spring-hangers 5 , spring-tie 6 , and flanged guard g , 120 arranged substantially as set forth, and for the purposes specified.

7. In combination with stationary longitudinal guard-rails situated between and above the level of the track-rails and attached to the longitudinal girders of an elevated-railway superstructure, a pair of truck-guards, each consisting of a flanged plate or shape of iron or steel attached, as described, to the transverse beams or frames of a car or locomotive truck, so as to move longitudinally with the motion of the truck in proximity to but not ordinarily in contact with the guard-rail on the structure, substantially as set forth. 125 130

8. The combination of the flanged truck-guard *g*, knees or braces *k*, and transoms of the trucks 2, substantially as set forth.

9. The combination, substantially as and for the purposes set forth, with the transoms of the trucks 2, of the truck-guard *g*, knees or braces *k*, stop or catch *c*, and bolts passing through spring-washers *v z*.

10. In a turnout or crossing of elevated-rail-way tracks carried upon the superstructure herein described, the combination, with the supporting girders, transverse brackets, and

lateral connections, of the main track-rails *T*, turnout or crossing rails *T'*, guard-rails *G*, and standards or braces *u*, supporting the guard-rails, substantially as shown, and for the purposes set forth. 15

In witness whereof I have hereunto signed my name in the presence of two subscribing witnesses.

EDWARD S. SHAW.
